UNITED STATES PATENT OFFICE.

OVERTON WINSTON, OF MINNEAPOLIS, MINNESOTA.

HEADLIGHT.

1,345,056.

Specification of Letters Patent. Patented June 29, 1920.

Application filed August 2, 1916. Serial No. 112,683.

To all whom it may concern:

Be it known that I, OVERTON WINSTON, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My invention relates to headlights, such as used on automobiles, and elsewhere, to give an approximately horizontal or forward projection of the light beam, and has for its object to materially improve the proportionate distribution of the light on and above the road.

In the accompanying drawings which illustrate the invention, like characters indicate like parts throughout the several views.

Referring to the drawings;

Figure 1 is a front elevation showing the improved reflector;

Figs. 2, 3 and 4 are sections taken respectively on the lines 2-2, 3-3 and 4-4 of Fig. 1, and showing also a two-filament light bulb positioned within the reflector; and

Fig. 5 is a diagrammatic view in oblique projection.

The reflector is indicated, as an entirety, by the numeral 5. Suitably supported within the reflector is an electric light bulb 6 which, as shown, is a two-filament bulb having one axial filament, the hot spot of which is at *a* and having a vertically offset filament, the hot spot of which is at *b*. The reflector 5 is formed with an axial passage 7 through which the shank of the bulb 6 is passed to a suitable socket or support, not shown. In all radial planes, the reflector preferably has a hyperbolic curve with a common axis through the point *a*, and which axis is coincident with line *y-y*, the axis of the reflector. The said axis *y-y*, also, is the axis of the bulb.

The preferred form of the reflector may be best made clear by assuming that it is generated by revolving the hyperbolic curve, represented by its radial section and having its focal center at *a*, on the axis *y-y*, while constantly changing the position of both extremities thereof, in respect to the

said axis and focal center, so that the said curve will have its maximum length when in its lowermost position and will have its minimum length when in its uppermost position. Stated in another way, under its first half revolution, for example, from its upper vertical position, on the axis *y-y*, said hyperbolic curve, at its outer portion, will move farther and farther radially away from the said axis, and at its inner extremity, will move farther and farther backward from the focal point *a*. The same fact may be expressed in still another way, by stating that, as the hyperbola is revolved downwardly on said axis *y-y*, (the axis of the hyperbola) it not only continuously increases its radial distance from said axis, but, at the same time, continuously shifts rearward its vertex or point of intersection with said axis, and thereby continuously increases the distance from said light source and focal center *a* of said vertex or point of intersection with said axis.

Under its second half revolution, the outer portion of said curve will move nearer and nearer to said axis and its inner extremity will move forward nearer and nearer to the focal center *a*, until the said curve again assumes its original position; or, otherwise stated, the surface of said reflector may be assumed to be generated by a conic revolved downwardly in opposite directions, on the approximately horizontal axis of the conic, while continuously increasing, at the same time, both its radial distance from said axis and the distance from said light source of its vertex or point of intersection with said axis. This produces a reflector, the rim or outer portion of which may be round or approximately round, and the reflecting surface of which will be without offsets or broken surfaces, but in which the upper portion of the reflector will be much closer to the focal center *a* than will the lower portion of said reflector. In a horizontal section, the reflector is preferably bisymmetrical, as shown in Fig. 4.

As preferably constructed, all radial sections of the reflector have a common focal center at *a*, and hence, are slightly different hyperbolic curves of a different focal length.

Referring now to Fig. 5, it should be noted that the vertical axial section of the

reflector consists of the two curves 2— x^1 and x^5 —2. The said curve 2— x^1 is the assumed initial position of the generating curve, and the curve x^5 —2 is the assumed terminal 5 position of the said generating curve; and here it should be noted that, during the semi-revolution from top to bottom, the vertex or point of intersection of the generating curve with the axis y — y , continuously 10 moves rearward from the most forward point x^1 to the most rearward point x^5 .

The curve of the horizontal axial section of the reflector is represented by the line 4— x^3 —4; and here it will be noted that 15 the vertex or point of intersection of said curve with axis y — y , at x^3 , is between the above noted points x^1 and x^5 .

The generating curve of the oblique axial section of the reflector, on the line 3—3, is 20 represented by the lines 3— x^2 and x^4 —3.

Here it may be further stated that the generating curves 2— x^1 and x^5 —2 are the curves illustrated in Fig. 2; that the generating curve 4— x^3 —4 is the curve represented in Fig. 4; and that the curves 3— x^2 and x^4 —3 are the curves represented in Fig. 25 3. The generating curves 3'— x^2 and x^4 —3' are curves that correspond, respectively, to the curves 3— x^2 and x^4 —3 of Fig. 5, taken 30 on the opposite diagonal plane from section 3—3.

Fig. 5 also clearly illustrates the already 35 stated fact that the conic or hyperbolic curve, in revolving from its assumed initial or uppermost position 2— x^1 , to its terminal or lowermost position 2— x^5 , continuously increases, at the same time, both its radial distance from said axis and the distance from said light source of its vertex or point 40 of intersection with said axis, and successively passes through the upper oblique, horizontal, and lower oblique positions, diagrammatically shown in Fig. 5; and this statement is true, regardless of, in which 45 direction the said generating curve is downwardly revolved on said axis.

The reflector illustrated in the drawings has, as above stated possible, a circular rim; and in Fig. 5, the center of the circle of 50 this rim is indicated at o , and, of course, is below the axis y — y . It follows from statements already made, and from the illustrations in Fig. 5, and also in Figs. 2, 3 and 4, that the axis y — y is the common axis of 55 all of the conics. The common focal center a is also clearly illustrated in Fig. 5. Fig. 1 also shows that the axis of the conic's revolution is located above the center of the possible circular cross section of the generated surface, which, in this instance, is 60 shown as being at the rim perpendicular to said axis.

From the foregoing description, it will be seen that, in the reflector illustrated, 65 two progressions or variations are involved

in the generation of the surface, to wit: one varying the distance between the focus and the vertex, and the other increasing the radial distance from the axis of revolution as the conic revolves from its uppermost 70 to its lowermost position. The first named progression affects the spread of the beam of light, and the second named progression causes a downward deflection of the reflected rays. In the illustrated form of the 75 reflector, the first named progression is secured by moving the vertex rearward as the conic revolves downward, which is by far the best way of securing this variation, because it enables the light to be kept on 80 the focus. The progression of the vertex of the conic, along the line of its axis, of itself, produces a radial progression, inasmuch as the cross sections of the generated surface, thereby produced, will not, generally speaking, be curves which are symmetrical, in respect to both the horizontal and vertical planes through the axis of revolution, due to the fact that the distance from the focus to the vertex is changed by 85 90 said progression of the vertex. The rate of this progression of the vertex of the conic can be predetermined for any desired specific form of reflector and this predetermination will fix the extent of the radial 95 progression, assuming the eccentricity of the conic to be constant. In the illustrated instances, the rate of the rearward progression of the vertex of the conic has been predetermined by the extent to which the axis 100 of its revolution is offset above the center of a circle, shown, in this instance, to wit: in Figs. 1 and 5 of the drawings, as located at the rim of the reflector.

The form of the reflector, illustrated in 105 the drawings, may be algebraically expressed by the following formula stated in rectangular cartesian coördinates in terms of X and Y .

The origin is the focus a , as shown in 110 Figs. 2, 3, 4 and 5 of the drawings.

The principal axis of the generating conic is taken as the X -axis, this being the line y — y , shown in said Figs. 2, 3, 4 and 5 of the drawings. 115

In the formula, d is the distance from the focus to the vertical plane of a circle, assumed, in this instance, to be located at the rim of a reflector, as best shown in Figs. 1 and 5 of the drawings. Said distance d is 120 measured on the axis of the conic.

In the formula, r is the radius of said circle.

In the formula, k represents the perpendicular distance from the center of said 125 circle to the axis of the conic.

Said elements d , r and k are arbitrary constants, predetermined by the designer.

In the formula, e denotes the eccentricity 130 of the generating conic, which, in the in-

stance illustrated in the drawings, is a hyperbola.

In the formula, θ denotes the angle between the vertical plane through the axis 5 of the conic and any radial plane through said axis.

In the formula, q denotes the ordinate of the hyperbola at the distance d from the focus in any one of the planes through the 10 axis of the conic. For example, in the illustrated form, it denotes the distance from the point at which the axis of the conic inter-

sects the plane of the circle, assumed to be located at the rim of the reflector, to any point on the circumference of said circle; 15 and which distance q is derived or can be computed by the following equation:

$$q - k \cos \theta \pm \sqrt{r^2 - k^2 \sin^2 \theta}$$

The equation of any axial section of the 20 reflector in a plane through the axis making an angle θ with the vertical plane through the axis is

$$\frac{\left[X + \left(\frac{-de^2 \pm e\sqrt{d^2 + q^2}}{e^2 - 1} \right) \right]^2}{\left(\frac{-de \pm \sqrt{d^2 + q^2}}{e^2 - 1} \right)^2} - \frac{Y^2}{\left(\frac{-de \pm \sqrt{d^2 + q^2}}{e^2 - 1} \right)^2 (e^2 - 1)} = 1$$

It is obvious that the hyperbola, in any 25 one of the radial planes, can be plotted by the use of this formula, since it is in terms of the known quantities enumerated above.

So far as my invention is concerned, the conic may have either a constant or a varying 30 eccentricity. The illustrations are based upon a constant eccentricity, but the curve in any one of the radial planes can be plotted for any assumed eccentricity, by the use of the above formula.

35 Commercial reflectors, designed as above described, may be made in a great many different ways. For instance, they may be pressed or cast against a pattern or form made with the proper outlines of the reflecting surface. The form or die, itself, may also be made in a great many different ways. One very feasible way of making the same would be as follows:

Take, for example, 180 rectangular plates, 40 wedge-shaped in cross section, the opposite lateral faces of which have each a divergence from each other of 2 degrees, the plates being of sufficient area to permit the corresponding 180 radial section curves to be plotted thereon. Then on one face of each plate, plot out the curve, in accordance with the above formula, using the sharp edge of the wedge as the axis of the reflector. Then, saw or cut or file these wedge-shaped plates 45 on the lines of the plotted curves. Then assemble together all of the wedge-shaped plates to form a solid mass. This will give a solid body with portions of the thick outer edges of the plates projecting outward 50 slightly beyond the plotted curves. Then, carefully file away the said projecting portions until the solid surface is reduced to a smooth exterior on the lines of the plotted curves. This, when the wedge plates are 55 properly secured together, by welding, or otherwise, will give a complete solid form or die on which the reflectors may be pressed or cast.

The peculiar contour of the above de-

scribed reflector will necessarily distribute 70 the reflected light in a manner radically different from the distribution secured from an ordinary reflector, wherein the surface is simply one of revolution, regardless of which one of the three conics, ellipse, parabola, or 75 hyperbola, may be used. In all of such ordinary reflectors, as is well known, the surface normals are in radial planes and intersect the axis of revolution, and, consequently, the incident ray, the surface normal 80 and the reflected ray are in one and the same radial plane; and the general result is that there will be an equal amount of light above and below the horizontal plane of the axis of the reflector, when the light is located at the focus.

The peculiar contour of this new reflector, above described, will have an entirely different effect in the distribution of the light, for the controlling reason that the surface 90 normals are necessarily out of and below the radial planes of the incident rays, and hence, it necessarily follows that all of the incident rays, which strike any portion of the reflector above the horizontal plane of 95 its axis will be deflected downward. The angle of incidence and the angle of reflection are, of course, the same, being equally inclined to the surface normal, but will vary for different rays, depending on the position 100 of the respective points, at which the incident ray strikes the said surface of the said reflector; and a large number of said incident rays will be so deflected downward, at such a degree, that the reflected rays will 105 reach the ground, and will coöperate with the rays reflected from that portion of the reflector below the horizontal plane of the axis to produce the desired illuminating effect. The same principles, in respect to surface normals and in respect to the deflection, of course, apply to that portion of the reflector below the plane of its horizontal axis, and hence, all reflected rays therefrom are 110 deflected downward to a greater degree and 115

strike the road nearer the reflector than rays deflected from the lower portion of the ordinary hyperbolic reflector. In other words, in this new and peculiar reflector, all of the 5 reflected light from the lower portion (to wit: that portion below the horizontal axis of the reflector) and a large part of the light from the upper portion (to wit: that portion above the said axis) becomes available for illumination of the road.

Nevertheless, notwithstanding the truth of the foregoing statements, some of the incident rays, which strike the portion of the reflector above its horizontal axis, will not 15 be deflected downward to such a degree as to pass below the horizontal plane of the axis of the reflector, and will coöperate with the unreflected rays from the light to afford all of the light needed above the horizontal 20 plane of the axis of the reflector.

Of course, it further follows, from the above stated facts, that objectionable glare and blinding effects are practically eliminated. Most of the light is thrown downward and reaches the ground, and hence, 25 there is no strong glaring beam to strike the face of an approaching driver or pedestrian.

Of course, it will be understood, that, while the drawings illustrate a reflector embodying my invention in what is its preferred form, so far as I now know, and that 30 while the specific description is directed to this specific form, it must, nevertheless, be understood that this specific form was selected for illustrative purposes only, as required by the law, and that I do not limit myself to that specific illustrated form. The design of the structure depends upon several variable factors, as hitherto made clear in 35 several different ways; and, of course, any change in any of these variable factors will, to some extent, vary the resulting surface generated, without departure from the invention; and, in the accompanying claims, I 40 desire to cover and protect my invention in 45 the broadest way possible.

What I claim is:

1. A headlight set for approximately horizontal projection and comprising a reflector 50 and a light source therein, said reflector having a surface substantially corresponding to a surface generated by a conic revolved in a downward direction on the approximately horizontal axis of the conic while increasing the distance from said light source of its vertex or point of intersection with said axis.

2. A headlight set for approximately horizontal projection and comprising a reflector and a light source therein, said reflector 55 having a surface substantially corresponding to a surface generated by a conic revolved in a downward direction on the approximately horizontal axis of the conic while increasing, at the same time, both its radial distance from said axis and the distance from said axis and the distance from said

light source of its vertex or point of intersection with said axis.

3. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance 70 from said light source of its vertex or point of intersection with said axis, and the vertices or points of intersection with said axis of the curves of the lower portion of the reflector being at greater distances from said light source than the vertices or points of intersection with said axis of the curves of the upper portion of the reflector.

4. A headlight set for approximately horizontal projection and comprising a reflector and a light source therein, a material portion of the reflector having a surface substantially corresponding to a surface generated by a conic revolved in a downward direction on the approximately horizontal axis of the conic while increasing the distance 80 from said light source of its vertex or point of intersection with said axis, and the radial distances from said axis of the curves of the lower portion of the reflector being greater than the radial distances from said axis of the curves of the upper portion of the reflector.

5. A headlight set for approximately horizontal projection and comprising a reflector and a light source therein, a material portion of the reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, and the vertices or points of intersection with said axis of the curves of the lower portion of the reflector being at greater distances from said light source than the vertices or points of intersection with said axis of the curves of the upper portion 90 of the reflector.

6. A headlight set for approximately horizontal projection and comprising a reflector and a light source therein, a material portion of the reflector having a surface substantially corresponding to a surface generated by a conic revolved in a downward direction on the approximately horizontal axis of the conic while increasing, at the same time, both its radial distance from said axis and the distance from said light source of its vertex or point of intersection with said axis, and the radial distances from said axis of the curves of the lower portion of the reflector being greater than the radial 100 distances from said axis of the curves of the upper portion 105 of the reflector.

110

115

120

125

130

tances from said axis of the curves of the upper portion of the reflector.

7. A headlight set for approximately horizontal projection and comprising a reflector and a light source therein, said reflector having a surface substantially corresponding to a surface generated by a conic revolved in a downward direction on the approximately horizontal axis of the conic while varying, at the same time, both its radial distance from said axis and the distance from said light source of its vertex or point of intersection with said axis, and the radial distances from said axis of the conics of the terminal portions of the surface thus generated being greater than the radial distances from said axis of the conics of the initial portions of the surface thus generated.

8. A headlight set for approximately horizontal projection and comprising a reflector and a light source therein, said reflector having a surface substantially corresponding to a surface generated by a conic revolved in a downward direction on the approximately horizontal axis of the conic while varying the distance from said light source of its vertex or point of intersection with said axis, and the vertices or points of intersection with said axis of the conics of the terminal portions of the surface thus generated being at greater distances from said light source than the vertices or points of intersection with said axis of the conics of the initial portions of the surface thus generated.

9. A headlight set for approximately horizontal projection and comprising a reflector and a light source therein, said reflector having its entire surface substantially corre-

sponding to a surface generated by a conic 40 revolved downwardly, in opposite directions, on the approximately horizontal axis of the conic while continuously increasing the distance from said light source of its vertex or point of intersection with said axis. 45

10. A headlight set for approximately horizontal projection and comprising a reflector and a light source therein, said reflector having its entire surface substantially corresponding to a surface generated by a 50 conic revolved downwardly, in opposite directions, on the approximately horizontal axis of the conic while continuously increasing, at the same time, both its radial distance from said axis and the distance from 55 said light source of its vertex or point of intersection with said axis.

11. A headlight set for approximately horizontal projection and comprising a reflector and a light source therein, the surface 60 of said reflector substantially corresponding to a surface generated by a conic revolved downwardly, on the approximately horizontal axis of the conic while continuously increasing its radial distance from said axis, 65 and the vertices or points of intersection with said axis of the conics of the lower portion of the reflector thus generated being at greater distances from said light source than the vertices or points of intersection 70 with said axis of the conics of the upper portion of the reflector thus generated.

In testimony whereof I affix my signature in the presence of two witnesses.

Corrections in Letters Patent No. 1,345,056.

It is hereby certified that in Letters Patent No. 1,345,056, granted June 29, 1920, upon the application of Overton Winston, of Minneapolis, Minnesota, for an improvement in "Headlights," errors appear in the printed specification requiring correction as follows: Page 2, lines 97-98, for the word "instances" read *instance*; page 3, line 18, equation; after the letter "q" insert the sign of equality (=); and that the said Letters Patent should be read with these corrections therein that the same may conform to the record of the case in the Patent Office.

Signed and sealed this 30th day of November, A. D., 1920.

[SEAL.]

L. B. MANN,

Acting Commissioner of Patents.
